INVENTOR

BY *Victor J. Evans*
ATTORNEY

UNITED STATES PATENT OFFICE.

EINAR H. BERG, OF CHICAGO, ILLINOIS.

WHIPPER.

1,416,597.

Specification of Letters Patent. Patented May 16, 1922.

Application filed August 13, 1920. Serial No. 403,366.

To all whom it may concern:

Be it known that I, EINAR H. BERG, a citizen of the United States, residing at Chicago, in the county of Cook and State of Illinois, have invented new and useful Improvements in Whippers, of which the following is a specification.

This invention relates to a whipper and has for its primary object the construction 10 of a whipper that may be manufactured at a relatively low cost without sacrificing the efficient operation thereof.

An object of the invention is the novel manner of constructing and associating the 15 parts so as to provide a more substantial construction at a minimum cost.

With these and other objects in view the invention will be better understood from the following detailed description taken in connection with the accompanying drawing 20 wherein:

Fig. 1 is an elevation of my improved whipper.

Fig. 2 is a sectional view.

Again referring to the drawing illustrating one construction of my invention the numeral 1 designates a bracket having a U shape body portion 2 and handle extension 3. Rotatably supported by the bracket is 30 the shaft 4 having formed thereon a collar 5 for regulating the position of the shaft. This shaft has rotatably supported thereon a sleeve 6 to the lower end of which is connected the flange 7 of the paddle 8 that is 35 provided with a plurality of holes 9 for increasing the agitation. Shaft 4 and sleeve 6 each have a gear 10 connected thereto meshing with the master gear 11 driven by the handle 12. This master gear is rotatably supported by the bracket as indicated

at 13. The lower end of the shaft 4 terminates in a ball 14 for reducing the frictional engagement of the shaft with the receptacle. A second paddle 15 also provided with holes 16 has a flange 17 secured to the shaft, and 45 spacing the paddles apart for allowing free movement thereof is the bearing 18.

From the foregoing description taken in connection with the accompanying drawing it will be apparent that I provide a whipper of few parts substantially associated and capable of co-acting in a manner to obtain the best results possible.

It is, of course, to be understood that the invention may be constructed in various 55 other manners and the parts associated in different relations and, therefore, I do not desire to be limited in any manner except as set forth in the claim hereunto appended.

Having thus described my invention what 60 I claim is:

A whipper comprising a shaft having a spherical end, a sleeve mounted upon the major portion of said shaft, a handle formed of flat metal bent to provide parallel 65 horizontal portions and a connecting vertical portion, said shaft extending through said horizontal portions and the lowermost of said horizontal portions resting upon the upper end of said sleeve, a collar pinned 70 upon said shaft and engaging the uppermost of said horizontal portions, beating paddles mounted one upon the lower end of said sleeve and one upon said shaft and in engagement with said spherical head, a bevel 75 gear rotatably carried by said vertical portion and means connecting said gear and shaft.

In testimony whereof I affix my signature.
EINAR H. BERG.
